(57) **CLAIM**

The ornamental design for the locking link, as shown and described.

DESCRIPTION

FIG. 1 is a perspective view of a locking link showing the new design;

FIG. 2 is a top view thereof;

FIG. 3 is a bottom view thereof;

FIG. 4 is a right side elevational view thereof;

FIG. 5 is a left side elevational view thereof;

FIG. 6 is an end plan view thereof; and,

FIG. 7 is the reverse end plan view thereof.

The broken line portions of the drawing are for illustrative purposes only and form no part of the claimed design.
